CLAIM

The ornamental design for a wearable robot, as shown and described.

DESCRIPTION

FIG. 1 is a front perspective view of a wearable robot showing our new design;
FIG. 2 is a front view thereof;
FIG. 3 is a rear view thereof;
FIG. 4 is a left side view thereof;
FIG. 5 is a right side view thereof;
FIG. 6 is a top plan view thereof;
FIG. 7 is a bottom plan view thereof; and,
FIG. 8 is a rear perspective view thereof.

The dashed broken lines in the figures illustrate portions of the wearable robot that form no part of the claimed design. The dot-dash broken lines in the figures define the boundaries of the claimed design and form no part of claimed design.

1 Claim, 8 Drawing Sheets

Related U.S. Application Data

a continuation of application No. 29/889,781, filed on Apr. 17, 2023, now Pat. No. Des. 1,059,606.
